(57) **CLAIM**

The ornamental design for a head rest as shown and described.

DESCRIPTION

FIG. 1 is a front, top, and left side perspective view of a first embodiment of a head rest showing my new design, shown in a closed position;

FIG. 2 is a rear, bottom, and right side perspective view thereof in an open position;

FIG. 3 is a rear, bottom, and left side perspective view thereof in a closed position;

FIG. 4 is a rear, top, and right side perspective view thereof in an open position;

FIG. 5 is a top view thereof in a closed position;

FIG. 6 is a bottom view thereof in an open position;

FIG. 7 is a left side view thereof in a closed position;

FIG. 8 is a right side view thereof in an open position;

FIG. 9 is a front view thereof in a closed position;

FIG. 10 is a rear view thereof in an open position;

FIG. 11 is a front, top, and right side perspective view thereof, shown in a closed position and in a state of use;

FIG. 12 is a front, top, and left side perspective view of a second embodiment of a head rest showing my new design, shown in a closed position;

FIG. 13 is a rear, bottom, and right side perspective view thereof in an open position;

FIG. 14 is a rear, bottom, and left side perspective view thereof in a closed position;

FIG. 15 is a rear, top, and right side perspective view thereof in an open position;

FIG. 16 is a top view thereof in a closed position;

FIG. 17 is a bottom view thereof in an open position;

FIG. 18 is a left side view thereof in a closed position;

FIG. 19 is a right side view thereof in an open position;

FIG. 20 is a front view thereof in a closed position;

FIG. 21 is a rear view thereof in an open position; and,

FIG. 22 is a front, top, and right side perspective view thereof, shown in a closed position and in a state of use.
